UNITED STATES PATENT OFFICE.

HANS T. BORSHEIM, OF CHARLES CITY, IOWA, ASSIGNOR TO HART-PARR COMPANY,
OF CHARLES CITY, IOWA, A CORPORATION OF IOWA.

WASHING MACHINE.

Application filed September 21, 1925. Serial No. 57,697.

This invention relates to improvements in washing machines, and more particularly to that type commonly known as the vacuum washer which employs a number of inverted 5 vacuum cups which are oscillated vertically to provide the agitating means for the clothes within the container. It usually requires a rather complicated mechanism for actuating the said vacuum cups.

10 It is, therefore, the object of my invention to provide an improved and simplified means for actuating the vacuum cups.

A further object is to provide means whereby the said cups and a portion of the actuating mechanism may be mounted on the tub 15 cover, in such a manner that the cups will be removed from the interior of the tub when the cover is moved to an open position, and in connection therewith provide means for connecting the actuating mechanism of the cover to the actuating mechanism supported on the main frame when the cover is in a closed position.

20 A further object is to provide means for 25 rotating the tub so as to change the position of the clothes relative to the cups, while the cups are being actuated.

A further object is to provide means for 30 simultaneously throwing the cup actuating mechanism and the tub actuating mechanism into and out of operation.

35 A further object is to provide improved means for mounting the cups relative to the actuating mechanism in such a manner that a certain amount of yieldability may be provided between the said actuating mechanism and the cups to somewhat reduce the violent action of the cups so that delicate clothing may be washed without tearing.

40 My invention consists in the construction, arrangement and combination of the various parts of the device, whereby the objects contemplated are attained, as hereinafter more fully set forth, pointed out in my claims, and 45 illustrated in the accompanying drawings, in which:

Figure 1 is a side elevation of my improved washing machine.

Figure 2 is a vertical sectional view.

50 Figure 3 is a detail sectional view taken on the line 3-3 of Figure 2.

Figure 4 is a detail sectional view taken on the line 4-4 of Figure 3.

55 Figure 5 is an enlarged detail view of the mechanism for yieldably mounting the cup

relative to its actuating mechanism, a portion of which is shown in section taken on the line 5-5 of Figure 2.

Figure 6 is a detail sectional view taken on the line 6-6 of Figure 5.

60 My improved washing machine comprises a frame having supporting legs 10 secured to a horizontally arranged web 11. The upper ends of the legs 10 are secured to an annular member 12. The central portion of the member 11 is provided with a hub 13. The said hub 13 is provided with a vertically arranged shaft 14, the upper end of which is rigidly connected to a web or frame member 15 which is designed to carry the bottom member 16 of 70 the tub 17. This provides means whereby the said tub 17 will be rotatively mounted about a vertical axis. The upper edge of said tub is mounted within the annular member 12 of the frame 10, as clearly shown in 75 Figure 2.

80 For imparting continuous rotary movement to the tub 17 while the machine is in operation, I have provided an annular rack 18 on the bottom side of the member 15, said rack being designed to mesh with a pinion 19 secured on the inner end of an inclined shaft 20. The outer end of said shaft 20 is provided with a beveled gear 21 in mesh with a beveled pinion 22, rotatively mounted on a 85 vertical shaft 23, said shaft having its lower end mounted in bearing members 24 and 25, which are formed in a gear casing 26, said gear casing being secured to the frame 10 by means of suitable rivets or bolts 27. The 90 lower end of the shaft 23 is provided with a worm gear 28 designed to mesh with a worm 29 mounted on the horizontally arranged shaft 30 operatively connected with a motor 31, said motor being mounted on a suitable bracket 32 supported by the legs 10. The pinion 22 is provided with a clutch member 33 designed to coact with a sliding clutch member 34 keyed to the shaft 23 and actuated by means of a yoke 35 supported on the 95 lower end of the vertical shaft 36. A spring 37 is provided on the lower end of the shaft 36 and beneath the member 35 so that the clutch member 34 is normally held out of engagement with the clutch member 33.

100 By this arrangement it will be seen that when the rod 36 is pressed downwardly the gear 32 will be thrown into operative relation with the shaft 23 and rotary movement will be imparted to the tub 17, the gearing 110

being so arranged that the speed of the said tub will be quite slow.

Pivots mounted on one side of the annular member 12 is a cover member 38 having the form of a segment of a sphere and having one edge of its inner face provided with a horizontally and inwardly extending bearing member 39, in which is rotatively and slidably mounted a shaft 40. The member 39 is provided with a longitudinal cavity 41 designed to receive the detachable bearing members 42 and 43. A packing gland 44 is provided at the outer end of each of said bearing members. The inner end of the shaft 40 is provided with a transversely and horizontally arranged arm 45. The outer end of the member 39 is provided with a downwardly extending portion 46 to which is pivoted an arm 47 parallel with the arm 45. Pivotally connected to the corresponding ends of said arms 45 and 47 is a sleeve 48. The lower end of each of the sleeves 48 is designed to slidably receive a sleeve 49, the lower end of which is connected with a vacuum cup 50. Extending longitudinally through the sleeves 48 and 49 is a rod 51, the lower end of which is connected to the cup 50 while the upper end of said rod is slidably mounted in a bearing member 52 within the sleeve 48. That portion of the rod 51 between the bearing members 52 and the cup 50 is provided with a spring 53, while the outer end of the rod 51 is provided with a head 54, said outer end also being provided with a spring 55 which rests between the bearing 52 and said head 54.

By this arrangement it will be seen that the cup 50 is yieldably supported relative to the sleeve 48. It will further be seen that the shaft 40 may be rocked, which will cause the ends of the members 47 to be oscillated, while the members 48 are held in parallel relation with each other and adapted to move vertically. The cups 50 are mounted within the tub 17 in the manner clearly shown in Figure 2 when the cover 38 is in a closed position.

The outer end of the shaft 40 is provided with a clutch member 56 which is slidably mounted in the cavity 41, and yieldably supported at its outer limit of movement by means of a spring 57. The head 56 is provided with an annular groove 58 designed to receive a pin 60 mounted on the inner end of a rotatively mounted shaft 61. Said pin 60 is located away from the center of the shaft 61 so as to form a sort of crank by means of which the head 58 will be moved inwardly as the said shaft is rotated. A handle 62 is provided for imparting said rotary movement. Said shaft 61 is also provided with slots 63 designed to receive a spring actuated locking bar 64 for locking the member 58 either at its outer or inner limit of movement.

Supported on the annular member 12 is a

gear housing 65 to which the upper end of the shaft 23 extends, said gear housing being supported by means of a bracket 66 and a tubular support 67. The lower end of said support rests in the upper end of the gear housing 26. That portion of the shaft 23 which extends through the housing 65 is provided with a circular disk 68 which is rigidly mounted to the shaft at an angle of forty-five degrees. The point of intersection between the center of said disk and the center of said shaft is in common alinement with the center of the shaft 40. The periphery of the disk 68 is provided with a rotatively mounted ring 69 provided with diametrically opposite pivot pins 70 which are pivotally mounted in a second ring 71, said ring 71 being provided with pivot members 72 arranged at right angles to the pivot members 70 and in alinement with the shaft 40. The inner one of the pivot members 72 is provided with a clutch member 73 which is designed to be engaged by the clutch member 56 when the cover 38 is in a closed position.

By this arrangement it will be seen that as the shaft 23 is rotated by means of the worm gear 28, an oscillatory movement will be imparted to the shaft 40 through the clutch members 58 and 73, which in turn will cause the cups 50 to be elevated and lowered within the tub, which is being continuously rotated at the same time. The springs 51 and 54 serve to act as shock absorbers, which somewhat modify the violent action of the cups as the reverse motion takes place, and thereby provides means whereby delicate clothes may be washed without injury, the action of the vacuum cups within the tub being too well known to require description.

Thus it will be seen I have provided a washing machine of simple, durable and inexpensive construction, which provides a mechanism of simple construction for imparting movement to the cups, which are mounted in the cover in such a manner that when the cover is elevated, the cups will be entirely removed from the interior of the tub permitting free access to the clothes therein.

It will further be seen that I have provided improved means for moving the clothes relative to the cups, which is accomplished by the continuous rotation of the tub.

It will further be seen that I have provided means whereby the cup actuating mechanism carried by the cover may be easily and quickly disconnected from the mechanism within the housing 65 by simply grasping the lever 62 and also the lever 75 which is operatively connected with the bar 64, said bar being disengaged from the notches 63, after which the lever 62 may be elevated causing the member 58 to be moved inwardly against the action of the spring 57 and the clutch members disengaged. In this connection it should be borne in mind that the lever 62 rests on

the upper end of the rod 36 when at its lower limit of movement, and serves to hold the said rod in its lowered position of movement against the spring 37, which causes the 5 tub to be thrown into operation. When the said lever 62 is elevated, the clutch members 34 will disengage the clutch member 33 and throw the tub out of operation, and at the same time the clutch members 58 and 73 are 10 disengaged.

It will further be seen that the tub member 17 may be easily and quickly removed from the frame by simply imparting an upward movement, which will cause the shaft 15 14 to disengage the hub 13, providing means whereby the tub may be easily and quickly removed when necessary.

I claim as my invention:

1. A washing machine comprising a supporting frame, a tub rotatively mounted for movement about a vertical axis, a cover member for said tub pivotally mounted to said frame, an agitator carried by said cover member, an actuating mechanism for said agitator also carried by said cover member, means carried by said frame for imparting movement to said actuating means when the cover member is closed, means for imparting rotary movement to said tub, and means for 20 simultaneously throwing said tub actuating means and said agitator actuating means into or out of operation.

2. In a washing machine, a supporting frame, a tub rotatively mounted therein, a cover member pivotally mounted to said frame, an agitator comprising a horizontally arranged shaft, a support for said shaft secured to said cover, an agitator arm fixed to the inner end of said shaft, a second arm 25 pivotally mounted to the lower end of said support and parallel with the first said arm, a vertically arranged sleeve pivotally mounted to the corresponding ends of said arms, the lower ends of said sleeves being open, a sleeve 30 slidably mounted in the open end of each of said sleeves, a cup rigidly secured to the lower end of each of the last said sleeves, yieldable means for supporting the last said sleeve against sliding movement within the first said sleeves, means for oscillating said shaft, means for continuously rotating said tub, and means for simultaneously throwing said tub actuating means and the means for oscillating said shaft into and out of operation.

3. In a washing machine, a supporting frame comprising a horizontally arranged web member having a central hub, a vertical shaft rotatively mounted in said hub, an annular frame member parallel with said web, a series of vertically arranged supporting legs connected to said annular member and said web member, a tub secured to the upper end of said vertical shaft, means for imparting rotary movement to said tub, a cover

member for said tub pivotally connected to said annular frame member, an agitator carried by said cover member, means supported by said annular frame member diametrically opposite from the pivot member of said cover 70 for imparting movement to said agitator, means for throwing said agitator into and out of operative relation with said actuating mechanism when the cover is in a closed position, and means for throwing the tub actuating means into and out of operation.

4. In a washing machine, a support having a longitudinal opening, bearing members detachably mounted in said opening, a shaft rotatably mounted in said bearings, packing 80 members adjacent to the outer end of each of said bearings, the inner end of said shaft being provided with a laterally extending arm, a second arm pivotally supported and parallel therewith, corresponding ends of 85 said arms being pivotally connected with a vertical sleeve, a second sleeve slidably mounted within the first said sleeve, a vacuum cup on the lower end of the second said sleeve, a rod extending centrally through 90 both of said sleeves, the upper end of which is slidably mounted in a bearing member in the upper end of the first said sleeve, the upper end of said rod being provided with a head, a spring on said rod between said head and 95 said bearing member, and a spring on said rod between said bearing member and said cup.

5. In a washing machine, a supporting frame comprising a horizontally arranged 100 web member having a central hub, a vertical shaft rotatively mounted in said hub, an annular frame member parallel with said web, a series of vertically arranged supporting legs connected to said annular member and said 105 web member, a tub secured to the upper end of said vertical shaft, means for imparting rotary movement to said tub, a cover member for said tub pivotally connected to said annular frame member, an agitator carried by 110 said cover member, means supported by said annular frame member diametrically opposite from the pivot member of said cover for imparting movement to said agitator, and means for simultaneously throwing said agitator operating means and said tub operating means into and out of operation with their respective members.

6. In a washing machine, a supporting frame comprising a horizontally arranged 120 web member having a central hub having a vertical bearing member, an annular frame member parallel with said web, a series of vertically arranged supporting legs for said annular member and said web member, a 125 vertical shaft for said bearing member, a horizontal web member for the upper end of said shaft, a tub supported on the last said web member, said second named web member having an annular gear rack on its bottom 130

surface, the upper end of said tub member extending within said annular member, a pinion gear for said rack, and means for imparting rotary movement to said pinion gear.

- 5 7. In a washing machine, a supporting frame comprising a horizontally arranged web member having a central hub having a vertical bearing member, an annular frame member parallel with said web, a series of
10 vertically arranged supporting members for said annular member and said web member, a vertical shaft for said bearing member, a horizontal web member for the upper end of said shaft, a tub supported on the last said
15 web member, said second named web member

having an annular gear rack on its bottom surface, the upper end of said tub member extending within said annular member, a pinion gear for said rack, means for imparting rotary movement to said pinion gear, a cover 20 member for said tub pivotally connected to said annular frame member, an agitator carried by said tub member adapted to swing out of said tub when the said cover is moved to an open position, and means for actuating 25 said agitating mechanism when the cover is in a closed position.

Des Moines, Iowa, September 10, 1925.

HANS T. BORSHEIM.
